BALLING OF YARNS AND THE LIKE

Frank Osborne, Adlington, Macclesfield, England,
assignor to Wm. Ayrton & Co. Limited, Manchester, England, a British company

Application December 4, 1946, Serial No. 714,023
In Great Britain December 17, 1945

11 Claims. (Cl. 242—2)

1

This invention relates to the balling of yarns and the like such as woolen yarns or other threads. Balling machines are known in which the flyer and ball spindle are geared together, and various sets of gearing are provided which can be interchanged to produce either what is known as an "ordinary lay" wind or a "lock-mesh" wind according to the relative speeds of rotation of the flyer and ball spindle.

These different types of wind have their individual characteristics and advantages. For instance, the "lock-mesh" type of wind has a pleasing external peripheral appearance and the ball is less liable to collapse or the yarn to become entangled as it is drawn off from inside the ball. On the other hand, the "ordinary lay" wind draws off rather more easily, especially while the centre of the ball is comparatively tight, and furthermore, the scroll effect which it provides at the ends of the ball is generally preferred, being sometimes said to give a better idea of the appearance of fabric made up from the yarn, than can be obtained from the end effect of the "lock-mesh" wind.

The "ordinary lay" is produced when the ratio of rotation of the flyer to the spindle is relatively high, the yarn at each turn of the flyer being laid against or close to the yarn of the preceding turn. In such arrangement a layer of adjacent diagonal yarns is being built up at opposite sides of the ball, which layers follow each other around the periphery of the ball. Owing to the diagonal direction of the wind, each layer, as it advances, overlies the earlier yarns of the other layer and is oppositely inclined. If a firm and solid ball is required the relative ratio of rotation is set so that according to the thickness of the yarn and diameter of the ball successive turns lie closely together. Wider spacing gives a looser ball.

On the other hand, for a "lock-mesh" wind the ratio between flyer and spindle is relatively low and is set for relatively wide spacing of the yarn for each turn of the flyer and so that the ratio is an integer plus a fraction or "differential." Thus in a simple "lock-mesh" the ratio might be 8.01 to 1 and in such case the flyer would lay 8 diagonal turns during the first rotation of the ball but the 9th turn, due to the "differential," would be laid close beside the first, the 10th close to the second and so on. During the first cycle or 8 turns, the opposite diagonals of yarn form several crossovers each diagonal lying over or under several of the others according to the value of the integer. During the second cycle the oppo-

5 site diagonals again cross each other adjacent to the crossovers of the first cycle and in such order that they are alternate in direction and produce a "braided" or "herringbone" effect which spreads around the periphery of the ball as winding progresses. The "differential" determines the spacing between parallel diagonals. If there is no "differential," the turns of each cycle would lie on top of those of the preceding cycle, instead of beside them, and would produce a "honeycomb" wind, not a "lock-mesh."

10 The object of the present invention is to combine the aforesaid advantages of each type of wind.

15 According to the invention the ball is wound with at least one layer of "lock-mesh" wind and at least one layer or thickness of "ordinary lay" wind. Preferably there is an outer layer of "lock-mesh" wind on top of a layer or thickness of "ordinary lay" wind.

20 The invention also comprises an improved machine to enable the type of wind to be changed without stopping the winding.

25 In the accompanying drawings:

Fig. 1 is a plan view of the improved machine certain of the shafts being shown broken and/or somewhat displaced from their true positions, for the sake of clearness.

30 Figs. 2 and 3 are sections to an enlarged scale, on the lines 2—2 and 3—3, respectively, of Fig. 1.

Fig. 4 is a section, also to an enlarged scale, on the line 4—4 of Fig. 3.

35 In one example of a ball of yarn or thread made in accordance with the invention, there is a first or inner layer of "lock-mesh" wind followed by "ordinary lay" wind and finished off with a layer of "lock-mesh" wind.

40 As a result, the ball has the peripheral external appearance of a "lock-mesh" wind whilst at its ends it has the scroll effect of the "ordinary lay" wind. In use, the initial layer of "lock-mesh" wind reduces the risk of entanglement in the initial stage of unwinding from the centre. After the inner "lock-mesh" layer has been unwound, the yarn draws easily as is characteristic of the "ordinary lay" wind whilst the outer "lock-mesh" layer holds together in known manner even when only a thin shell of thread is left, especially if this be supported by an external band.

45 The improved winding machine illustrated is arranged to wind balls in the manner above described, and may be for the most part of normal construction, its side frames 5 being connected at front and back by horizontal angle-bars 6, 7.

The tops of the side frames 5 are also connected

together at the front of the machine by a cross-member 8 whose ends are provided with forwardly projecting brackets 9 upon which are angularly adjustable, about the common axis of their pivots 10, a pair of arms 11, these latter being fixed to the ends of a housing 12 extending horizontally across the front of the machine.

A longitudinal shaft 13 in this housing is provided at spaced positions with skew gears 14, whose mating gears 15 are on short transverse spindles 16 carrying collapsible winding heads at their inner ends. One of these latter is shown at 17 in Fig. 1.

Journalled in the cross-member 8, and in a further cross member 18 behind the latter, are a plurality of hollow spindles 19 arranged with their axes parallel to the side frames 5 and carrying flyers 20, each of which is adapted for cooperation with one of the winding heads 17.

In each case the material to be wound (indicated at 21 in Fig. 2) traverses the flyer spindle 19 and is threaded through the flyer 20, which latter is caused to gyrate around the winding head 17 to produce thereon a ball 22. The length and form of the ball 22 is determined mainly by the angle at which the winding head axis is set in relation to the axis of the flyer spindle 19, and is variable by appropriate adjustment at the pivots 10.

Each flyer spindle is provided with a centrally arranged skew gear 23, which meshes with one of a number of mating gears 24 on a shaft 25 extending from side to side of the machine and provided at one end with a fast-and-loose pulley system 26.

Adjacent one side of the machine the shaft 25 carries a pinion 27 which drives a gear wheel 28 on a parallel shaft 29, this latter projecting beyond the adjacent side frame 5 (in which it is supported) and driving, through gear-pairs 30, 31 and 32, 33, a short spindle 34 also supported in the side frame 5.

The inner end of this spindle 34 is connected through bevel gears 35, 36 to a worm 37 set transversely of the shafts 25, 29 and driving a worm wheel 38 on a cam shaft 39 whose ends are journalled in the lower parts of the two side frames 5.

The machine is arranged to stop automatically as soon as the cam shaft 39 has been turned through one revolution, its rotation being effected either by the gearing above described, or through the medium of an alternative gear-train of different ratio. By this means the cam shaft may be turned either quickly or slowly according to whether short or long balls are to be wound.

Adjacent the other side of the machine, the shaft 25 carries a second pinion 40 which drives a gear wheel 41 on a parallel shaft 42 journalled in two spaced castings 43 which connect the rear angle-bar 7 to the cross-member 8.

The ends of the shaft 42 project beyond the castings 43 and carry gears 44, 45, bell-crank levers 46 capable of angular adjustment about the axis of the shaft 42 being mounted on the latter between the castings 43 and the gears aforesaid.

Corresponding arms of the bell-cranks 46 lie alongside the castings 43 and are formed with arcuate slots 47 concentric with the shaft 42, these slots 47 being engaged by clamping bolts or screws 48 whereby the bell-cranks are secured in their adjusted positions.

The other arms of the bell-cranks are formed with longitudinal slots 49 in which are adjustably secured outwardly-projecting spindles 50.

One of these spindles carries a compound gear 51, 52 whose elements mesh, respectively, with the gear 44 and a second gear 53 at one end of a shaft 54 which is mounted in one of the castings 43 alongside the shaft 42, this shaft 54 making spigotal engagement at 55 with a coaxial shaft 56 supported in the other casting 43.

The second spindle 50 also carries a compound gear, one element 57 of which is driven from the gear 45, whilst the other element 58 drives a gear 59 on the shaft 56.

The gear trains 44—51—52—53 and 45—57—58—59 are of different ratio so that one of the shafts 54, 56 will be driven faster than the other from the shaft 42. Further gears, interchangeable with (for example) the compound gears 51, 52 and 57, 58, may be supplied with the machine to provide a variety of alternative speed ratios for the shafts 54, 56; the angular adjustment provided for the bell-cranks 46 enabling these idle gears, however arranged, to be meshed with their driving and driven members.

As shown in Fig. 4, the shaft 54 has fixed at its inner end a female clutch cone 60 adapted for engagement by one operative portion 61 of a double-ended male clutch member 62 which is freely rotatable on the adjacent end of the coaxial shaft 56. The other operative portion 63 of the clutch member 62 is adapted to cooperate with a second female cone 64 fixed upon the shaft 56.

The male clutch member 62 is formed with a ring of gear teeth 65 in constant mesh with a gear 66 on a parallel shaft 67, this latter being supported partly by one of the castings 43 and partly by a bracket 68 on the rear angle-bar 7 of the machine.

A gear 69 at the outer end of the shaft 67 drives a gear 70 on the spindle 71 of a pulley 72 carried by the bracket 68 and this pulley 72 is connected by a belt 73 to a second pulley 74 freely rotatable on one of the pivot pins 10 associated with the gear housing 12 for the winding heads 17. The bracket 68 may be made angularly adjustable about the axis of the shaft 67 to allow the tension of the belt 73 to be varied.

Associated with this pulley 74 is a gear 75 driving, through an idler gear 76 carried by the adjacent housing arm 11, a gear 77 at one end of the shaft 13.

The latter can thus be driven (through the gears 65, 66, 69, 70, 75, 76, 77) from either of the coaxial shafts 54, 56 according to which of the latter is clutched to the member 62 carrying the gear 65.

For this purpose the clutch member 62 is made slidable endwise on the shaft 56 under the influence of an actuating lever 78 which is freely pivoted on a spindle 79 disposed at right angles to the shaft 56. The ends of this spindle 79 may be supported by the rear angle-bar 7 and a bracket 80 depending from the cross-member 18.

The upper arm of the lever 78 is forked as at 81 and the limbs of the fork engage trunnions 82 on a divided muff 83 which embraces a circumferential groove 84 in the clutch member 62.

The lower arm of the lever 78 has a V-shaped end 85 which cooperates with a catch-lug 86 of similar shape on a swinging lever 87 pivoted upon one of the side frames 5, and urged upwardly by a spring 88 which tends to hold the lug in contact with the lever end 85.

Fixed to the shaft 39 is a double-sided face cam 89, whose operative surfaces are engaged by bowls 90 at the lower ends of two freely-pivoted levers

91 which depend from the spindle 79 and are drawn towards one another by a tension spring 92.

The cooperation of the V-shaped lug 86 with the end 85 of the lever 78 presses the latter towards one or the other of its extreme positions; that is to say it always holds the driven clutch member 62 in engagement with one or other of the two driving cones 60, 64.

The cam 89 comprises a central or hub portion having flanged rings (whose outer edges provide 10 the operative surfaces 93) secured thereto by bolts 94 passed through elongated holes in the rings, so that recesses 95 in both faces 93 may be angularly adjusted with reference to one another and to the hub portion aforesaid. Each such recess has its leading end perpendicular to the plane of the cam 89 and the other end inclined.

As illustrated, the cam 89 rotates in the direction of the arrow (Fig. 2), with the right hand cam recess somewhat in advance of the other, the bowls 90 associated with both levers 91 running on the level faces of the cam until first one, and then the other, bowl reaches the adjacent recess.

In Fig. 4, the right-hand lever 91 is shown in the position it assumes when allowed by the cam 89 to move inwards under the action of the spring 92, and it will be appreciated that this inward swing of the lever 91 results in an adjustable abutment 96 thereon coming sharply into contact, at a predetermined instant, with the lower arm of the lever 78, whose V-shaped end 85 is thus forced past the catch lug 86 into the position shown. In this way the driven clutch member 62 is disengaged from the cone 60 and brought firmly into engagement with the other cone 64, being locked in this position by the catch lug 86.

On further movement of the cam 89, the right-hand lever 91 is forced outwards as its bowl 90 rides up the inclined end of the adjacent cam recess 95, the spring 92 remaining under the full tension thus imposed until the cam 89 has turned sufficiently to bring its other recess 95 beneath the bowl of the left-hand lever 91, which then moves inwards under the pull of the spring 92. As the adjustable abutment 96 carried by the left-hand lever 91 strikes the lower arm of the lever 78, the latter is operated to shift the clutch member 62 back into engagement with the cone 60, in which position it is locked by the catch lug 86.

The part of each lever 91 adjacent the bowl 90 is provided with a flat-based angular projection 97 which is normally just clear of the cam surface 93. As soon as the bowl 90 passes over the end of the associated recess 95, this projection 97 comes into operation and results in a sharp inward movement of the lever 91 as its lower end enters the cam recess.

In operation, the machine above described can be adjusted so as to wind balls having any desired combination of the "ordinary lay" and "lock-mesh" winds, or alternatively it can be used to wind balls throughout with either type of wind. However the balls are wound, the change-over from one type of wind to the other is effected without stopping production merely by shifting the clutch member 62 endwise as above described.

In the construction illustrated, the change-over is produced automatically by means of the adjustable cam 89 and associated actuating mechanism, but obviously it may be effected manually if desired, the object in either case being to instantaneously alter the rotational speed of the shaft 13 in relation to that of the shaft 25, and hence the relative speeds of the winding heads 17 and flyers 20.

Winding machines have, of course, already been fitted with variable speed gearing which is changeable during running to provide for alteration of the pitch of an "ordinary lay" wind to suit the gradually increasing diameter of the ball, but not providing a change in the kind of wind.

Obviously, the invention includes any desired combination of the two kinds of wind, with or without variation of pitch therein and is not limited to the details of the example above described in so far as such details may be modified without departing from the nature of the invention.

I declare that what I claim is:

1. A machine for balling yarns and the like comprising at least one winding head, a flyer adapted to lay the yarn upon said winding head, a main driving shaft, gearing of fixed ratio connecting said driving shaft to said flyer, a lay-shaft permanently geared to said driving shaft, separate variable gear-trains of different ratio driven from said layshaft, aligned clutch shafts rotated through the medium of said gear-trains, female cone clutch members fixed to said aligned shafts, a double-ended male clutch member interposed between said female members, gearing of fixed ratio connecting said male clutch member to said winding head, and means for moving said male clutch member so as to disengage it from one, and engage it with the other, of said complementary clutch members for varying the type of wind.

2. A machine for balling yarns and the like comprising at least one winding head, a flyer adapted to lay the yarn upon said winding head, a main driving shaft, gearing of fixed ratio connecting said driving shaft to said flyer, a lay-shaft permanently geared to said driving shaft, separate variable gear-trains of different ratio driven from said layshaft, aligned clutch shafts rotated through the medium of said gear-trains, female cone clutch members fixed to said aligned shafts, a double-ended male clutch member interposed between said female members, gearing of fixed ratio connecting said male clutch member to said winding head, a double-sided cam geared for rotation at a predetermined speed relatively to said driving shaft, swinging levers adapted to be operated alternately by opposite sides of said cam, and a third lever adapted to be displaced first in one direction and then in the other by the alternate operation of said swinging levers, said third lever being operatively connected to said male clutch member so that the latter is periodically disengaged from one, and engaged with the other, of said complementary clutch members to vary the type of wind.

3. A machine for balling yarns and the like on a winding spindle which includes means for driving both a winding spindle and a flyer adapted to lay the yarn thereon, said driving means comprising in series a first change speed mechanism giving alternative high and low ratios between its input and output members to change the speed ratio between the spindle and the flyer abruptly during the winding process, so as to change the type of wind in a ball from "ordinary lay" to "lock mesh" or vice versa without stopping the machine, the input member of that mechanism having a constant speed ratio relatively to the flyer, and a second drive mechanism receiving the drive from said first mechanism and giving a predetermined ratio between the output member of said first mechanism and the winding

spindle for the close winding of particular yarn sizes.

4. A machine for balling yarns according to claim 3, further characterised in that the change-over from one type of wind to the other (e. g. from "ordinary lay" to "lock mesh," or vice versa) includes a clutch device adapted to bring into engagement alternative gear trains of different gear ratios whereby the output member is driven either at one speed to give "ordinary lay" wind or at another speed to give "lock mesh" wind, said output member driving a member which is permanently geared to the winding spindle through the said further change speed mechanism, the flyer being driven at constant speed.

5. A machine for balling yarns according to claim 2 wherein each of said swinging levers has an adjustable threaded member positioned so as to engage and displace said third lever when the swinging levers are operated.

6. A machine for balling yarns according to claim 4 and having adjustable means for varying the time of speed change in the first-named mechanism.

7. A machine for balling yarns according to claim 4, further characterised in that the clutch device comprises a driven element connected by gearing to the winding spindle and disposed between two coaxial driving elements rotating at different speeds, said driven element being engageable with either of said driving elements.

8. A machine for balling yarns according to claim 7, further characterised in that the driven element of the clutch device comprises a double-ended cone which is slideable to bring either end thereof into engagement with the adjacent coaxial driving element, the latter being of complementary shape.

9. A machine for balling yarns according to claim 7, further characterised in that the driven

element is actuated automatically through the medium of a rocking lever controlled by a cam rotating at a pre-determined speed relatively to the flyer.

10. A machine for balling yarns according to claim 8, further characterized in that the driven element is actuated automatically through the medium of a rocking lever controlled by a cam rotating at a predetermined speed relatively to the flyer.

11. A machine for balling yarns according to claim 9, further characterized in that the rocking lever is positively displaced from one extreme position to the other through the medium of spring-loaded levers engaging opposite sides of the cam.
